HENRY E. BROCK

BY

Connie S. Nickey
ATTORNEY.

UNITED STATES PATENT OFFICE

HENRY E. BROCK, OF DETROIT, MICHIGAN, ASSIGNOR TO WOODSTEEL BOX CORPORATION, OF DETROIT, MICHIGAN, A CORPORATION OF MICHIGAN

BOX

Application filed April 8, 1929. Serial No. 353,337.

This invention relates to boxes and the object of the invention is to provide a box for heavy duty and rough handling which is braced so as to withstand strains from all 5 sides and angles which would break an ordinary box.

Another object of the invention is to provide a box of steel and laminated wood construction so tied together so that it has great 10 rigidity and cannot be readily crushed or broken.

A further object of the invention is to provide a box having a top and bottom steel frame containing insertible laminated wood 15 panels, the top and bottom frames being tied together so that the combination of the panels and the frames provides a box which will not rack or twist under strain.

A further object of the invention is to provide a box in which the different parts may 20 be replaced with a minimum of labor when worn out or when the panels are broken.

These objects and the several novel features of the invention are hereinafter more 25 fully described and claimed and the preferred form of construction by which these objects are attained is shown in the accompanying drawings in which—

Fig. 1 is a perspective view of a box employing my invention.

Fig. 2 is an enlarged section taken on line 2—2 of Fig. 1.

Fig. 3 is a section taken on line 3—3 of Fig. 1.

Fig. 4 is an enlarged section taken on line 4—4 of Fig. 1.

Fig. 5 shows an alternative fastening for the box corners.

Fig. 6 is a section taken on line 6—6 of Fig. 5.

Fig. 7 is a section showing a means for securing the panels in the channel frame.

Fig. 8 is a plan view of an alternative form of box having round corners.

Fig. 9 is a section taken on line 9—9 of Fig. 8.

Fig. 10 is a section taken on line 10—10 of Fig. 8.

Fig. 11 is a section taken on line 11—11 of Fig. 10.

Fig. 12 is a section taken on line 12—12 of Fig. 8.

Fig. 13 is a perspective view of one of the metal box corners.

The box comprises a rectangular upper 55 frame member 1 which is channel shaped in cross section as shown in Fig. 2 and is provided with an internally extending horizontal flange 2. The lower rectangular frame member 3 is of substantially the same form 60 in cross section and is provided with an internally extending flange 4. The side panels 5 and end panels 6 of the box are formed of laminated wood and are positioned in the channels 1 and 2 as will be understood from 65 Fig. 2.

The panels 5 and 6 are brought into end to end relation as shown in Fig. 3 and in order to cover this corner a sheet metal angle iron 7 is positioned thereover and the lower 70 channel 3 is extruded at the corner 8 so as to provide space into which the angle member 7 may be positioned. A similar extrusion is formed in the upper frame member to support the upper end of the member 7 as will 75 be understood from Fig. 1. In this way the corner member 7 is supported at each corner of the box and protects the corner and improves the appearance by covering the ends 80 of the panels. The box is tied together at the four corners by the bolts 9 shown in Figs. 1 and 4 which extend through the flanges 2 and 4 at the corners and by turning the nuts up on the bolts 9 the top and bottom 85 rectangular frame may be drawn together to apply a pressure on the panels. These bolts secure the portions of the box together into a unitary structure and thus a box is provided which will not rack in use. It will be 90 noted that in this structure the panels 5 and 6 form the compression members while the bolts 9 at the four corners form the tension members and the channels or rectangular frames 1 and 3 are utilized for applying the 95 tension to the compression members. By means of the flanges 2 and 4 of the top and bottom frame members these flanges act as strengthening ribs to hold the top and bottom frames in rectangular form and prevent the

box from racking by a pressure on the sides or corners thereof.

Further strength is attained by the provision of the triangular gussets 10 welded to the flanges 4 in each bottom corner of the box and through which the bolts extend. The laminated end panels 6 may be provided with hand holds having a sheet metal rim member 11, as shown in Fig. 1. While I have shown the tension members 9 as bolts they may be long rivets which are upset at each end to place a pressure on the panels the rivets being preferably upset sufficiently to draw the frame members 1 and 3 together and prevent looseness.

An alternative arrangement for securing the box together at the corners consists of a wire 12 which is bent inwardly at each end and inserted through apertures provided therefor in the frame members 1 and 3 and the corner members 7 and the inner ends of the wire are bent over as shown in Figs. 5 and 6. One or two of these wires may be provided at each corner and the corresponding panels are apertured to allow the ends of the wire to be inserted therethrough.

Occasionally through misuse one of the panels may be staved in, in which case it is necessary to replace the panel. When this occurs, if bolts are used, it is merely necessary to remove the nuts from the bolts and lift the top frame member off the box, at which time the broken panel may be removed and a new panel inserted. When long rivets are used it is necessary to cut the rivets and remove them and utilize new rivets when reassembling the box.

When wires are used, as shown in Figs. 5 and 6, the wires may be cut and replaced by new wires when the box is reassembled. Also when the box is taken apart any piece of the box which is bent, broken or otherwise damaged may be readily replaced and by means of the metal edges provided about the edges and corners of the box the box is well protected and will stand a great amount of wear and rough handling.

As shown in Figs. 1 and 2 the flanges 2 and 4 of the frame members 1 and 3 strengthen the box by the angle construction and at the same time a bottom may be provided and attached to the lower flange 4 in any desired manner and a top may be provided and attached to the upper flange 2 if desired to provide a closed receptacle. When the box is used as a bottle crate it is left open at the top and bottom as shown and a wire bottle rack is positioned directly on the lower metal flange 4.

If desired the channel frame members 1 and 3 may be provided with inturned lugs 13, as shown in Fig. 7, which engage the panels and hold them in their respective channels. These lugs 13 are pressed into the channel and as the panel is inserted there-

between the panel is gripped thereby and is held from displacement.

In Figs. 8, 9, 10, 11, 12 and 13 an alternative form of box is shown having round corners. In this form the frame channel 14 at the top and bottom is provided with rounded corners and the inner flanges 2 and 4, of the type shown in Figs. 1 and 2, are left off to increase the size of the box opening.

The panels are positioned within the channels 14 which are provided at the top and bottom of the box but do not extend to the corner of the box like the panels do in Fig. 1. The corners each consist of a rounded sheet metal member 15, shown in Fig. 13, having an inturned flange 16 at the top and bottom and a panel bracket 17 at each side welded to the member 15 and adapted to receive the adjacent panel. The corners of the channel frame are extruded at 18, as shown in Figs. 8 and 11, to receive the member 15 and the flanges 16 and when thus assembled the panels extend into and are held by the brackets 17, as shown in Figs. 10 and 11. In this way the member 15 covers the ends of the panel and at the same time provides a rounded corner for the box. In order to secure the box together the top and bottom member 14 at each corner is provided with an extruded aperture 19 and the member 15 is provided with an aperture 20 in the top and bottom flanges 16 into which the extruded metal about the apertures 19 extends. An elongated rivet 21 is then extended through the apertures 19 and 20 in the frame members 14 and the corner member 15 and each end of the rivet is upset at 22 to fill the extruded apertures 19 flush with the top of the respective frame members. In this way the box is tied together at the four corners very firmly and the rivets 21 at the same time are out of the way as they extend through a space normally occupied in the remainder of the box by the laminated panels as will be understood from Fig. 9.

The brackets 17 which engage the ends of the panels are sufficiently short so that they do not interfere with fitting the frame members on the corners, the ends of the brackets 17 terminating short of the channel frame members 14 as will be understood from Fig. 10. It will thus be noted that the box in either form is tied together by only four tension members so that the minimum number of rivets, bolts or other securing means is utilized.

From the foregoing description it becomes evident that the device is very simple and efficient in operation, is very strong in construction, may be readily taken apart or reassembled and provides a device which accomplishes the objects described.

Having thus fully described my invention, its utility and mode of operation, what I

claim and desire to secure by Letters Patent of the United States is—

1. A box comprising a pair of continuous frame members formed of sheet metal and providing a channel and having a flange extending inwardly of the frame from one edge of the channel, the frames being positioned with the open side of the channels facing each other, a wood panel member having its opposite edges positioned in the channels of the respective frames, a bottom member supported on the flange of the lower frame, bolts extending through the flanges of the respective frame members adapted to hold the same rigidly in assembled relation, and metal elements extending between the two frames on the exterior of the box limiting the extent to which the frame members may be drawn together by the bolts thereby preventing collapse of the wood panels.
2. A box consisting of a pair of sheet metal rectangular frame members of channel form in cross section and positioned with the open sides of the channel facing each other, a wood panel for each of the four sides of the box having the opposite edges supported in the respective channels, a metal corner member of angle form covering the meeting edges of the wood panels and extending into the channel of each frame member, a tensioning means for drawing the frame members toward each other to place the parts under compression strains, the angle members limiting the extent to which the frames may be drawn together and thereby limiting the pressure to which the panel members may be subjected.

In testimony whereof I sign this specification.

HENRY E. BROCK.
